UNITED STATES PATENT OFFICE.

ARVID F. CARLIN, OF MAMARONECK, NEW YORK.

COMBINED SHELF AND BRACKET.

Application filed January 15, 1923. Serial No. 612,674.

To all whom it may concern:

Be it known that I, ARVID F. CARLIN, a citizen of the United States, and a resident of Mamaroneck, in the county of West-
5 chester and State of New York, have invented certain new and useful Improvements in Combined Shelves and Brackets, of which the following is a specification.

10 The object of the present invention is to provide an improved form of shelf and bracket, in which the bracket is readily detachable from the shelf to facilitate the packing and transportation of such devices,
15 and which can be easily assembled for attachment on a wall or in a corner.

In the accompanying drawings illustrating embodiments of my invention Figure 1 shows a corner shelf with its bracket in
20 position for use.

Fig. 2 is a vertical section on the line
2—2 of Fig. 1.

Fig. 3 shows the bracket member de-
tached.

25 Fig. 4 shows a modified form of bracket for a corner shelf.

Fig. 5 shows the latter in position for use.

Fig. 6 shows a shelf with a similar form of bracket at each end.

30 Fig. 7 is a bottom view of the latter de-
vices.

Fig. 8 is a section on the line 8—8 of
Fig. 6.

Fig. 9 shows the bracket shown in Fig. 6.

35 Fig. 10 shows a modified form of the lat-
ter bracket.

As shown in Figs. 1—5, I provide a cor-
ner shelf 2 that is substantially triangular,
40 with the sides 3 and 4 meeting at a right
angle, and connected by a front curved edge
6. One form of bracket for this shelf com-
prises a wire 7 formed into an eye 8 at the
upper portion, and then extended forward
45 at 9 with the extremities 10 projecting up-
wardly. This bracket portion is placed in
the upright position at the rear of the shelf
with the portion 9 engaging the bottom and
the end 10 extended into a suitable aper-
50 ture 11 in the shelf, see Fig. 2. The loop
8 extends in a vertical plane and can en-
gage a short corner portion 12 of the shelf,
but preferably extends above the shelf to
receive a suitable holding device such as
55 a screw 13 or a nail whereby it can be sus-
pended.

The lower end of the upright wire 7 con-

ncts with a pair of arms that project for-
ward to engage the sides 3 and 4 of the
shelf at their forward portions. As shown,
I provide arms 14 and 15 that at their 60
middle portion are bent to form a loop
16, that is engaged by an eye 17 on the
lower end of the upright rod 7. The arms
14 and 15 are inclined upwardly and have
their extremities bent at 18 and 19 to enter 65
suitable apertures 20' and 21' in the shelf
lower face near the edges 3 and 4 respec-
tively.

In Figs. 4 and 5 I show a slight modifi-
cation in which the same arms 14 and 15 70
are used with the loop 16, but the upright
member is formed double. In this arrange-
ment the upright member is formed by
wires 20 and 21 that form a loop 22 that
engages the loop 16' of the side arms. Each 75
of these arms 20 and 21 is formed at the
top similar to the arm 7, and which has
an eye 22', a horizontal portion 23 and a
bent end 24. These ends are extended into
suitable apertures 25 and 26 in the shelf 80
adjacent the corner 12.

It will be understood that a device of this
kind will strongly support the shelf on the
wall, and can be easily dismounted by
simply withdrawing the bent ends from the 85
apertures in the shelf 2. The arm 7 or the
two arms 20 and 21 are folded in the plane
of the side arms 14 and 15, and the bracket
can be simply laid on the shelf and will
occupy very little space for storage or trans- 90
portation. When it is to be used, the bent
ends are inserted in the apertures in the
lower face of the shelf and it is at once
ready for use.

Another modification is shown in Figs. 95
6—10, in which I provide a pair of brack-
ets substantially similar to the bracket
shown in Fig. 3. In this case I employ an
oblong shelf 30 shown of rectangular form.
The brackets are identical and as shown in 100
Fig. 9, comprise arms 31 and 32 extending
at an angle. The upper end of the arm 31
is bent to form an eye 33 that will lie in
the rear vertical plane of the shelf, and
the end portion is bent forward at 34 be- 105
neath the shelf, with the extremity 35 bent
upwardly to enter a suitable aperture 36
in the shelf. The eye 33 will extend a short
distance above the shelf and will receive
a suitable screw 37 passing in through the 110
eye to support the brackets and shelf.

The other arm extends forward and up-

ward to suitably engage the shelf bottom wall near the front. As shown in Fig. 8 the end portion 38 is bent laterally to enter a suitable aperture 39 in the bottom of the shelf.

In a modification shown in Fig. 10 the end portion 40 of the arm is given a slight downward bend to engage a staple 42 in the bottom of the shelf 43.

10 In these forms of brackets I provide means for holding a rod adapted to support a towel or the like. As shown the arm 32 is bent to form a loop 44 at the middle portion, that is substantially U-shape and 15 opens upwardly. I provide a bar 45 having an annular groove 46 at each end, at which portions the bar can engage the loops 44 by merely moving it downwardly in the loop that will be snugly engaged by the 20 walls of the groove and retain the bar in position. This bar also serves to brace the two brackets against lateral movement.

It will be readily seen that this device can be quickly taken apart by merely slipping 25 the bent ends out of apertures, and removing the towel bar. These members will occupy a very small space for packing or transportation. And they can be very easily assembled by merely slipping the 30 bent ends of the brackets into the proper apertures and then applying the towel bar.

As shown in Figs. 4 and 5, the arms 14 and 15 are provided with loops 44^a, and 44^b, that are both vertical and parallel, and 35 which support a towel bar 45' at each portion. The towel bar is furnished with annular grooves 44' near each end at which portions the bar engages the loops 44^a, and 44^b, to removably support the bar underneath the shelf, to receive a towel or the like.

What I claim is:—

1. In a corner shelf bracket a substantially triangular shelf having apertures near its rear edges, and a bracket comprising a wire having a vertical portion with the end bent in a vertical plane to form a supporting eye, and the extremity bent below the eye to extend forward some distance under the shelf and then extended upwardly to detachably engage a shelf aperture, the lower end of the vertical portion being bent to form an eye, the bracket also including inclined portions formed by a wire having a loop at its middle portion engaging said lower eye on the vertical portion, said latter wire having each portion beyond the eye extended forwardly and upwardly to engage one rear side of the shelf respectively at an apertured portion in proximity to the forward part of the shelf.

2. In a corner shelf bracket, a substantially triangular shelf having apertures near its rear edges, and a bracket comprising a wire having a vertical portion with the end

bent to a vertical plane to form a supporting eye, and the extremity bent below the eye to extend forward some distance under the shelf and then extended upwardly to detachably engage a shelf aperture, the lower end of the vertical portion being bent to form an eye, the bracket also including inclined portions formed by a wire having a loop at its middle portion engaging said lower eye on the vertical portion, said latter wire having each portion beyond the eye extended forwardly and upwardly to engage one rear side of the shelf respectively at an apertured portion in proximity to the forward part of the shelf, said inclined bracket portions being bent to form a loop of U-shape opening upwardly, and a bar provided near each end with an annular groove whereby the bar is engaged by the loop to support the bar on the bracket be- 85

3. In a corner shelf bracket, a substantially triangular shelf having apertures near its rear edges, and a bracket comprising a wire having a pair of upwardly extending integral portions connected by a loop at the bottom, each portion having the upper end portion bent in a vertical plane to form a supporting eye and the extremity bent below the eye to extend forward some distance under the shelf and then extended upwardly to detachably engage a shelf aperture, the bracket also including inclined portions formed by a wire having a loop at its middle lower portion engaging said lower eye on the said upwardly extending portion, said latter wire having each portion beyond the eye extended forwardly and upwardly to detachably engage one rear side of the shelf respectively at an apertured portion in proximity to the forward part of the shelf.

4. In a corner shelf bracket, a substantially triangular shelf having apertures near its rear edges, and a bracket comprising a wire having a pair of upwardly extending integral portions connected by a loop at the bottom, each portion having the upper end portion bent in a vertical plane to form a supporting eye and the extremity bent below the eye to extend forward some distance under the shelf and then extended upwardly to detachably engage a shelf aperture, the bracket also including inclined portions formed by a wire having a loop at its middle lower portion engaging said lower eye on the said upwardly extending portion, said latter wire having each portion beyond the eye extended forwardly and upwardly to detachably engage one rear side of the shelf respectively at an apertured portion in proximity to the forward part of the shelf, said inclined bracket portions bent to form a loop of U-shape opening upwardly, and a bar provided near each end with an annular groove whereby the bar is en- 130

gaged by the loop to support the bar on the bracket below the shelf.

5. In a shelf and bracket, a shelf provided with bracket apertures, and one or 5 more brackets each comprising a wire bent to form an upright part to engage the rear of the shelf by its top portion, and a part inclined forwards and upwards to engage the front portion of the shelf, the upright 10 bracket part having the end portion bent in the vertical plane of the rear shelf edge to form a supporting eye with the extremity bent below the eye to extend forward some distance under the shelf and then extended upwardly to detachably engage a shelf aperture, the forward bracket portion being removably secured to the forward portion of the shelf. 15

Signed at New York, N. Y., on January 6, 1928.

ARVID F. CARLIN.
